UNITED STATES PATENT OFFICE

2,457,026

CLOTHESPIN

Joseph F. Bergantino, San Francisco, Calif.

Application February 7, 1947, Serial No. 727,267

1 Claim. (Cl. 24—137)

1

The invention, in general, relates to devices for suspending articles of clothing, including fabrics as well as curtains and drapes and the like, from a line. More particularly, the invention relates to an improved clothespin affording complete protection to the clothes or other suspended articles from becoming soiled, torn or otherwise damaged.

Practically all modern types of clothespins have been so constructed as to incorporate therein a resilient member, such as a coil spring or the like, for urging the gripping jaws of the pin together to hold a garment or article of clothing therebetween. Some of these prior clothespins containing such springs are so made as to present one or both termini of the spring in an exposed condition with the result that clothing or fabrics suspended by the pin accidentally become torn. Moreover, many of these prior types of clothespins require the use of small pieces of cloth or paper to prevent contact of the suspended article with the wire or fabric line for preventing soiling of the articles. The present invention is directed to a springless clothespin so constructed as to obviate the foregoing disadvantages of prior constructions.

A primary object of the present invention is to provide an improved clothespin affording a positive gripping action upon clothes or articles to be suspended which is in direct ratio to its positive gripping action on the line upon which the pin is mounted or attached.

Another important object of my invention is to provide an improved clothespin of the indicated nature which is further characterized by its adaptability to suspend clothes and other fabrics from a line free from contact with the line.

A still further object of the invention is to provide an improved clothespin of the aforementioned character having a minimum of parts and being relatively inexpensive to produce.

Another important object of the present invention is to provide an improved clothespin which can be removably attached to a line after having first attached clothing, fabrics or other articles to the pin so that the suspending of the clothes to the line can be performed in a single operation.

Other objects of the invention, together with some of the advantageous features thereof, will appear from the following description of a preferred embodiment of the invention which is illustrated in the accompanying drawings. It is to be understood that I am not to be limited to the precise embodiment shown, nor to the precise

2

arrangement of the parts thereof, as my invention, as defined in the appended claim, can be embodied in a plurality and variety of forms.

Referring to the drawings:

Figure 1 is a perspective view of a preferred embodiment of the invention.

Figure 2 is a front elevational view of the preferred embodiment of the invention shown in open position, the full and dotted lines indicating the construction.

Figure 3 is an elevational view, partly in section, of a preferred embodiment of the invention indicating the operative position thereof as attached to a line and holding an article, this view being taken on the line 3—3 of Figure 4.

Figure 4 is a side elevational view of the preferred embodiment of the invention.

In its preferred form, the improved clothespin of my invention preferably comprises a combination hook and gripping jaw element, a combination lever and gripping jaw element, together with a pin for pivotally fastening the two elements together; said pin serving as a fulcrum for the lever action in attaching the pin to a line.

As particularly depicted in Figures 1 to 3, inclusive, of the accompanying drawings, my improved clothespin consists of but three main parts including a combination hook and gripping jaw element 11 which is formed with an elongated slot 12 in the hook portion 13 thereof as well as a transverse opening 15 extending through the same at the approximate longitudinal center thereof, and with a series of notches 14 in the gripping jaw portion 16 thereof, such notches being depicted in dotted lines in Figure 2 of the drawings and in full lines in Figure 3 of the drawings. In addition, the improved clothespin includes a combination lever and gripping jaw element 17 wherein the lever portion 18 is made narrow as compared to the gripping portion 19 thereof, such lever 18 terminating short of the hook portion 13 of element 11 and passing through the slot 12 of the hook 13 when the pin 20 is in open position, as indicated by the full line showing of Figure 1 and the dotted line showing of Figure 2 of the drawings. The gripping jaw portion 19 of the element 17 is formed with a serrated side, as indicated by the reference numeral 20, and the serrations 20 of the jaw portion 19 corresponding in position to the positions of the recesses or notches 14 of the gripping jaw portion 16 of the element 11. Thus, with the pin 20 in closed or operative position suspended from a line 21, see Figure 3 of the drawings, the serra-

tions 20 enter the notches 14 with a portion of an article 22 gripped therebetween.

In accordance with my invention, the combination hook and gripping jaw element 11 is pivotally connected to the combination lever and gripping jaw element 17 by means of a pivot pin 26 which is so located as to function as a fulcrum for the lever portion 18 of element 17, with the line 21 bearing against the upper extremity of the lever when the hook 13 is slipped over or suspended on the line 21. This lever action effects a positive gripping action on the article of clothing 22 between the jaws 16 and 19, and the gripping action at the jaws is in direct ratio to the gripping action effected between the hook 13 and the lever 18 with the line 21 gripped in between.

While the improved clothespin of my present invention can be fabricated of any suitable material, such as relatively hard wood, or a stainless metal such as stainless steel, I preferably mold the elements from a plastic material such as a phenolic or urea condensate, and also employ such plastic material for the pivot and fulcrum pin 26. Thus, there is afforded a moistureproof, hard clothespin of relatively great strength to withstand hard usage with no exposed metal parts to become rusty and, consequently, avoiding all likelihood of clothing or articles becoming rusted or otherwise soiled from contact with the pin. Moreover, since no spring is contained in my improved clothespin, there is no danger of clothing or fabrics becoming torn or otherwise damaged from termini of wire springs or the like.

It is to be appreciated that my improved clothespin can be attached to a clothesline with one hand and in a single operation after first disposing and gripping clothing or articles between the jaw portions of the elements 11 and 17. To effect this result, it is only necessary to first place the clothing between the gripping jaws and press the lever 18 with the thumb or finger towards the closed portion of the hook 13. Thereafter, with the one hand dispose the hook over the line 21 by

fitting the line between the open portion of the hook and the lever 18, all as clearly shown in Figure 3 of the drawings.

It is to be understood that the appended claim is to be accorded a range of equivalents commensurate with the advance made over the prior art.

I claim:

A clothespin comprising a combination hook and gripping jaw element; the hook having an elongated slot therein and said element having a transverse opening therethrough at the approximate longitudinal center thereof, a combination lever and gripping jaw element extending through said transverse opening of said first named element approximately at its longitudinal center with the gripping jaws of the elements aligned in opposed relationship; the lever of said second named element passing through the slot of the hook upon the opening of the clothespin, and a pivot pin piercing both said elements at their approximate longitudinal center to connect the elements for pivotal movement; said pivot pin serving as a fulcrum when the clothespin is suspended from a clothesline forcibly to urge the gripping elements toward one another.

JOSEPH F. BERGANTINO.
